WINDOW WITH REMOVABLE PANE

Isaac D. Sillman, New York, N. Y.

Application December 5, 1945, Serial No. 632,943

12 Claims. (Cl. 20—56.2)

1

The present invention is directed to windows and more particularly to such a structure wherein access may be had from the inside of a window to the outside for purpose of cleaning the same.

It is, of course, necessary to periodically clean windows and in windows of the double-hung type, it is extremely difficult to adequately clean the outside of the windows without special equipment. It is highly desirable that access be had to the outside of all of the panes of glass from the inside, without undue strain on the part of the window washer and without the necessity for using special apparatus. It is possible to have safety hooks on the outside of the window frame and the window washer to have a safety belt whereby said washer may stand upon the outside of the window ledge and wash the windows from the outside. However, this is not feasible in the great majority of dwelling places, as it requires considerable skill and there is a grave element of danger involved.

The present invention is intended and adapted to overcome the difficulties of access to the outside of window panes in double-hung windows and to provide a construction wherein from the inside of a building, the outside of said panes may be easily and readily reached for washing.

It is among the objects of the present invention to provide a structure of a window sash wherein at least one of the panes thereof shall be movable in such a manner as to provide an opening through which the hand of the worker may be inserted for the purpose of cleaning the outside of the window.

It is also among the objects of the present invention to provide a structure wherein one of the panes of a multiple pane window sash may be made so movable and access to the other panes be obtained through the opening of the movable pane.

It is still further among the objects of the present invention to provide a movable pane structure which will allow the pane to be shifted in position or entirely removed from the panel in which it is mounted.

In practicing the present invention, there is provided any of the usual forms of window sashes which are mounted in a suitable window frame. Such sashes may be made of wood or metal construction or of any other suitable material. In the case where each window sash contains a plurality of window panes each mounted in a separate panel, one of the panes is made movable. It is provided with a frame binding the edges of the glass and a slot is provided in a side member of the sash through which the pane may be moved.

2

The sides and bottom of the panel in which the movable frame fits is provided with specially designed spring members which act to hold the pane in position and are also adapted to provide a waterproof joint between the pane and the panel. To facilitate movement of the pane, there is also provided one or more handles in the frame thereof, which handles are normally in a concealed position and which may be utilized to obtain a firm grip on the frame in order to move the pane.

In another aspect of the invention where the window sash contains a single relatively large pane, the same or a different type of structure may be provided. According to a modification of the present invention, the pane is provided with a closely fitting frame and is mounted within the sash. The mounting may include a frame with hinge members which directly unite the frame with the sash so that when it is desired to clean the window, the frame is rotated about the hinge to open the same inwardly. In place of direct hinges, other means may be provided as, for instance, a sliding hinge joint whereby the frame may be pulled forwardly, whereby a hinge is provided and the frame may then be rotated about the hinge or may be entirely removed from the sash.

In the accompanying drawing constituting a part hereof and in which like reference characters indicate like parts,

Fig. 1 is a front elevational view of a standard form of window embodying a pair of relatively slidable window sashes and containing the present invention;

Fig. 2 is an enlarged fragmentary cross-sectional view taken along the line 2—2 of Fig. 2 and turned 90° from the position indicated by said line, showing particularly the manner in which the fixed or movable panes are held in the sash;

Fig. 3 is an enlarged fragmentary cross-sectional view of the movable window pane, illustrating a modified form of frame surrounding the same;

Figs. 4 and 5 are side elevational views of two modified forms of spring members which line the bottom and side of the panel for the movable frame;

Fig. 6 is a fragmentary enlarged top plan view of the sash shown in Fig. 1, illustrating particularly the locking means for the same;

Fig. 7 is a fragmentary side elevational view of the top of the slidable window pane, illustrating the handles for moving the same;

Fig. 8 is a top plan view thereof;

Fig. 9 is a front elevational view of a window sash containing a single pane made in accordance with the present invention;

Fig. 10 is a vertical cross-sectional view thereof taken along the line 10—10 of Fig. 9;

Fig. 10a is a modification of the embodiment shown in Fig. 10;

Fig. 11 is a fragmentary cross-sectional view of an upper corner of the structure of Fig. 9, illustrating means for preventing the pane from opening too far;

Fig. 12 is an enlarged side elevational view of handles and latches for holding the pane in its closed position;

Fig. 13 is a fragmentary enlarged cross-sectional view showing the junction of movable pane and sash of Fig. 9; and

Fig. 14 is an elevational view of a modified form of spring for said sash.

The window frame 1 is provided with upper and lower sashes 2 and 3. In a central panel of at least one sash is a movable pane 4 fitting into panel 5 formed by cross pieces 6. The other panes 7 are held in position by putty 8 or the like.

Movable pane 4 is provided with a sash frame 9 preferably of thin metal or plastic and of a single piece of material which is bent around and closely fits against the glass. It is bent around the corners so that the thickness of metal at the corners is approximately the same as the remainder of the frame. Cement may be introduced between the frame 9 and glass 4.

Flat spring lining consisting of leg 10 having an angular leg 10' is inserted in the panel and secured thereto by tacks 11 along leg 10' thereof. The other leg is bent as shown at 12 substantially parallel to 10 and has a right angle portion 13 adjacent the bottom of the groove of the panel. As preferably constructed, it does not quite touch the bottom of the panel. A bowed portion 14 is provided and the end thereof is placed a sufficient distance from element 12 to allow limited movement of said end of portion 14.

In place of a unitary frame 9 there may be provided a two-part frame, as shown in Fig. 3. It consists of an angle member having legs 15 and 16, said member being fitted to one side and the edges of glass 4. A similar angle member having legs 17 and 18 is fitted on the opposite side of glass 4 with leg 18 fitting over leg 16.

Various forms of springs may be used, as for example that shown in Fig. 4 is provided with legs 10 and 10', the latter being secured to the bottom of the groove of the panel. Leg 12 is integral with the body portion 19. In Fig. 5 a modified form of spring is shown wherein there are two members, one of which consists of legs 20 and 21, with a body portion 22 extending from the latter. A second spring member 23 is secured to member 20 by rivets 24. It also has a body portion 25. By this structure, a greater amount of springiness is obtained both at the side and at the bottom of the groove.

The top of the pane frame 9 as shown in Figs. 7 and 8 is provided with and a part of a relatively wide edge 26 integral with frame 9 and extending a substantial distance above the top of the pane.

4. A pair of slots 28 are provided in member 26 and handles 29 are introduced to cover the same. Slot 27 is provided along the top edge of sash frame 3 above pane 4. Means may be provided to prevent accidental removal of handles 29 after they have been inserted. Each handle has a pair of depending legs 30 and wings 31 and 32 extending laterally. Normally they rest upon 75

the top edge 33 of glass 4 and handle 29 is almost flush with member 26. In use one grasps handles 29, thereby lifting wings 31 and 32 against the inside of member 26 and the pane may be lifted and slid in its groove with the strain being distributed on the frame and thus there is no danger of cracking or breaking the glass.

Provision is made so that not only may the window sash be locked but also the sliding pane held against accidental displacement. For this purpose there is provided a latch 34 pivoted at 35 on the top of sash 3 in a position adjacent to slot 27. A keeper 36 is secured opposite pivot 35 on sash 2. Latch 34 when in the closed position shown in Fig. 6 not only locks the sashes against relative movement, but also locks glass 4 against movement. When latch 34 is opened, it may be opened partially to still overlay glass 4 or fully to allow the glass 4 to be pulled out of place.

In the modification of the invention shown in Figs. 9 to 12, there is provided a window sash 40 having a single glass or other pane therein. A frame 42 is provided around glass 41. Hinges 43 are provided parallel with the lower edge of and attached to the mounting thereof, whereby pane 41 may be rotated about a horizontal axis. In Fig. 10a, the pane 41 is slidable.

The frame and glass are covered by a facing 44 having extending flanges 45 around the edges thereof to cover at least partially the window sash. A hinge may be formed therein, as shown in Fig. 10, said hinge comprising a depending portion 46 on facing 45 in substantial contact with cylindrical portion 47 of sash 40. The facing further has a recessed inner portion 48 complementary to cylinder 47. In this case, when it is desired to open the pane 41, the assembly is pulled forward until recess 48 contacts cylinder 47, as shown in dotted lines in Fig. 10. Then the frame may be pivoted about such a hinge or it may be lifted clear of the window sash.

To assist in the handling of the pane, a pair of handles 49 is usually provided on the sides of flange 45 by rivets 50. Also, on the facing are rivets 51 passing through slots 52 in angle members 53 constituting a slidable latch. Keepers 54 extend from sash 40 through suitable openings in flange 45 and act as the keepers for the latches. Thereby the window pane may be held securely in place when it is in closed position.

In order to provide a weather-tight joint, the face of the sash adjacent to the frame is provided with a specially constructed spring member made of flat material. It consists essentially of a flat portion 55 adapted to contact the edges of the frame or glass 41 and integral with a parallel portion 56 which contacts with the window sash. An angle 57 at the opposite end of 56 rests in the bottom of the recess or groove of the window sash. It may be held in position by means, not shown. Also to retain the spring in its proper position, it is provided with an angular portion 58 integral with portion 55. A sufficient space 59 remains between parts 56 and 53 to allow of a compressive movement of the spring due to pressure by the glass.

Preferably means are provided so that when the glass is in open position, its movement is limited. This is accomplished by providing ears 60 and 61 on the facing and sash, respectively. A cord, chain, cable or the like has its ends held in said ears. When the window is in closed position, the cable is held within the sash and is not visible from the outside. It is of sufficient length so

that when the glass 41 is pivoted about its hinges, the correct amount of opening is provided.

An alternate arrangement to weather-proof the glass 41 consists in providing cement, putty or the like 63, whereby frame 42 is sealed on to glass 41. The spring consists of a bottom member 64, a bowed portion 65 contacting one side of the glass and a flat portion 66 bearing against sash 40. In Fig. 14 is shown a still further type of spring capable of use in the present invention. It consists of a member 68 which is angular in cross-section and a co-extensive angular member 69 integral therewith. A bowed portion 70 extends from angle 69.

There has been provided in the present invention double action flat spring linings which cover the side and bottom of the grooves of the sash. Thereby the pressure of the movable pane allows the linings to retract in two directions which gives complete protection against weather. Also, the flat spring linings have the additional important function of holding the sliding pane in any position in which it may be placed. The flat spring linings also take up vibration and prevent rattling or loosening of the movable pane.

Although the invention has been described setting forth several embodiments thereof, the invention is not limited thereto but many variations in the details may be made within the scope of the invention. For instance, a single solid or laminated pane in a sash may be made sliding instead of pivoted. The frame surrounding the pane is of uniform thickness and may be of a single piece or of any number of parts. The movable window may be utilized as a ventilator or one or both of the window sashes may be equipped with the same. Each has the advantage that the appearance of the movable pane is indistinguishable from the fixed panes.

The spring linings may be made of bronze or any other ferrous or non-ferrous metal which is resistant to weather. The size, thickness and strength of the spring linings vary with the conditions and the particular application. The form of the spring linings may be varied greatly as many forms can be adapted for the particular purpose involved, provided that sufficient space is provided for compression of the spring linings due to the pressure of the glass thereon. The form and character of the handles 29 may be changed at will and the wings 31 and 32 may be made foldable against legs 30 for the purpose of inserting into member 28. The slots for the handles 29 may be partly closed to hold the handles in position after insertion, so as to prevent handles 29 from dropping too far to be conveniently grasped. Any type of cement, putty or the like may be used to seal the glass to its frame. The framed pane may be fitted with springs on the inner side of the sash frame, the pane frame fitting snugly against the sash frame. In Fig. 2, member 6 may be on the weather or outer side of the sash, and putty 8, or equivalent thereof on the inner side of the sash.

These and other variations in the details and construction may be made within the spirit of the invention and the invention is to be broadly construed and not to be limited except by the character of the claims appended hereto.

I claim:

1. In a double-hung window having a pair of window sashes slidably mounted in a window and cooperating to close the window opening, a sash having a plurality of window panes mounted in panels, the improvement which comprises a rec-

tangular slidable pane, a frame fitted about the edges of said pane, said pane being mounted in a panel of said sash, a slot in a side of said sash, said pane being slideable through said slot, a flat spring lining on the sides and bottom of said panel, said lining having a compressible springy portion on the sides and bottom thereof, said portion extending into the space occupied by said pane frame when in closed position said pane being adapted to compress said spring portion when said pane is in closed position, the top of said pane frame fitting into said sash slot to close the same.

2. In a double-hung window having a pair of window sashes slidably mounted in a window and cooperating to close the window opening, a sash having a plurality of window panes mounted in panels, the improvement which comprises a rectangular slidable pane, a frame fitted about the edges of said pane, said frame being of one piece bent at the corners of said pane at about 90°, the thickness of said frame at said corners being about the same as the rest of said frame, said pane being mounted in a panel of said sash, a slot in a side of said sash, said pane being slideable through said slot, a flat spring lining on the sides and bottom of said panel, said lining having a compressible springy portion on the sides and bottom thereof, said portion extending into the space occupied by said pane frame when in closed position, said pane being adapted to compress said spring portion when said pane is in closed position, the top of said pane frame fitting into said sash slot to close the same.

3. In a double-hung window having a pair of window sashes slidably mounted in a window and cooperating to close the window opening, a sash having a plurality of window panes mounted in panels, the improvement which comprises a rectangular slidable pane, a frame fitted about the edges of said pane, said frame being formed of a pair of angle members on opposite sides of said pane to provide a channel, said pane being mounted in a panel of said sash, a slot in a side of said sash, said pane being slideable through said slot, a flat spring lining on the sides and bottom of said panel, said lining having a compressible springy portion on the sides and bottom thereof, said portion extending into the space occupied by said pane frame when in closed position, said pane being adapted to compress said spring portion when said pane is in closed position, the top of said pane frame fitting into said sash slot to close the same.

4. In a double-hung window having a pair of window sashes slidably mounted in a window and cooperating to close the window opening, a sash having a plurality of window panes mounted in panels, the improvement which comprises a rectangular slidable pane, a frame fitted about the edges of said pane, said pane being mounted in a panel of said sash, a slot in a side of said sash, said pane being slideable through said slot, a flat spring lining on the sides and bottom of said panel, said lining having a compressible springy portion on the sides and bottom thereof, said portion extending into the space occupied by said pane frame when in closed position, said pane being adapted to compress said spring portion when said pane is in closed position, the top of said pane frame fitting into said sash slot to close the same, a latch at the top of said sash adjacent to the side of said slot adapted to lock said sash and said slidable pane simultaneously by being

placed across the top of said slot and held in a keeper.

5. In a double-hung window having a pair of window sashes slidably mounted in a window and cooperating to close the window opening, a sash having a plurality of window panes mounted in panels, the improvement which comprises a rectangular slidable pane, a frame fitted about the edges of said pane, said pane being mounted in a panel of said sash, a slot in a side of said sash, said pane being slidable through said slot, a flat spring lining on the sides and bottom of said panel, said lining having a compressible springy portion on the sides and bottom thereof, said portion extending into the space occupied by said pane frame when in closed position, said pane being adapted to compress said spring portion when said pane is in closed position, the top of said pane frame fitting into said sash slot to close the same, at least one handle on the top of said frame, extensions on said handle below and within said top and wings on said extensions, whereby said handle may be raised when in use.

6. In a double-hung window having a pair of window sashes slidably mounted in a window and cooperating to close the window opening, a sash having a plurality of window panes mounted in panels, the improvement which comprises a rectangular slidable pane, a frame fitted about the edges of said pane, said pane being mounted in a panel of said sash, a slot in a side of said sash, said pane being slidable through said slot, a spring lining the sides and bottom of said panel, said lining having a flat portion secured in said panel and a free bowed portion adapted to be contacted by said frame, said lining having a compressible springy portion on the sides and bottom thereof, said portion extending into the space occupied by said pane frame when in closed position, said pane being adapted to compress said spring portion when said pane is in closed position, the top of said pane frame fitting into said sash slot to close the same.

7. A window comprising a sash, a rectangular slidable pane, a frame fitted about the edges of said pane, a slot in a side of said sash, said pane being slidable through said slot, a flat spring lining on three of the sides of said sash, said lining having a compressible spring portion extending into the space occupied by said pane frame when in closed position, said pane being adapted to compress said spring portion when said pane is in closed position.

8. A window comprising a sash, a rectangular slidable pane, a frame fitted about the edges of said pane, said frame being cemented to said pane, a slot in a side of said sash, said pane being slidable through said sash slot, a flat spring lining on three of the sides of said sash, said lining having a compressible spring portion extending into the space occupied by said pane frame when in closed position, said pane being adapted to compress said spring portion when said pane is in closed position.

9. A window comprising a sash, a rectangular slidable pane, a frame fitted about the edges of said pane, a slot in a side of said sash, said pane being slidable through said sash slot, a flat spring lining on three of the sides of said sash, said lining having a compressible spring portion extending into the space occupied by said pane frame when in closed position, said pane being adapted to compress said spring portion when said pane is in closed position, a slot in said pane frame, a handle on the top of said pane frame and extending through said slot into said frame, said slot being partially closed to hold said handle in position.

10. A window comprising a sash, a rectangular slidable pane, a frame fitted about the edges of said pane, a slot in a side of said sash, said pane being slidable through said sash slot, a flat spring lining on three of the sides of said sash, said lining having a compressible spring portion extending into the space occupied by said pane frame when in closed position, said pane being adapted to compress said spring portion when said pane is in closed position, said lining being substantially parallel with the face of said pane.

11. A window comprising a sash, a rectangular slidable pane, a frame fitted about the edges of said pane, a slot in a side of said sash, said pane being slidable through said sash slot, a flat spring lining on three of the sides of said sash, said lining having a compressible spring portion extending into the space occupied by said pane frame when in closed position, said pane being adapted to compress said spring portion when said pane is in closed position, said lining being substantially parallel with the edge of said pane.

12. A window comprising a sash, a rectangular slidable pane, a frame fitted about the edges of said pane, a slot in a side of said sash, said pane being slidable through said sash slot, a flat spring lining on three of the sides of said sash, said lining having a compressible spring portion extending into the space occupied by said pane frame when in closed position, said pane being adapted to compress said spring portion when said pane is in closed position, and putty on the outside of said lining.
